(57) **CLAIM**

The ornamental design for a time indicating label, as shown and described.

DESCRIPTION

FIG. 1 is a perspective view of a time indicating label;

FIG. 2 is a top view thereof;

FIG. 3 is an edge view thereof;

FIG. 4 is a bottom view thereof;

FIG. 5 is an opposite edge view thereof;

FIG. 6 is a side view thereof; and,

FIG. 7 is an opposite side view thereof.

The broken lines shown in the figures are for illustrative environmental purposes only and form no part of the claimed design.
